UNITED STATES PATENT OFFICE.

ALEXANDER J. SOCIA, OF SYRACUSE, NEW YORK, ASSIGNOR, BY MESNE ASSIGNMENTS,
TO LIBERTY NATIONAL BANK, TRUSTEE, OF SYRACUSE, NEW YORK.

PRESSING MACHINE.

Application filed October 31, 1923. Serial No. 671,897.

To all whom it may concern:

Be it known that I, ALEXANDER J. SOCIA, a citizen of the United States, and a resident of Syracuse, in the county of Onondaga and 5 State of New York, have invented a certain new and useful Pressing Machine, of which the following is a specification.

This invention relates to pressing machines, such as are used particularly in 10 pressing garments, clothing, laundry and the like, which machines are actuated by power; and has for its object a simple and compact actuating mechanism so arranged that locks and latches are unnecessary and 15 so that the power cannot be transferred to the movable pressing element except when such element has been brought down toward the work far enough to prevent injury to the operator or, in other words, so that the 20 power cannot be effectively applied while it is possible for the operator to have his hands or fingers between the pressing elements but, if applied, merely works idly on the movable pressing element.

25 The invention consists in the novel features and in the combinations and constructions hereinafter set forth and claimed.

In describing this invention, reference is had to the accompanying drawings in which 30 like characters designate corresponding parts in all the views.

Figure 1 is a side elevation of the pressing machine embodying my invention, the pressing elements being shown in closed position, 35 preliminary to the actuation of the power lever by the cam to apply heavy pressure.

Figure 2 is a fragmentary side elevation showing a pressing element in open position.

Figure 3 is a fragmentary detail view of 40 the parts of the power mechanism.

Figure 4 is a detail view of a lever mechanism for connecting the motion transmitting mechanism to the motor driven actuator.

45 Figure 5 is an elevation similar to Figure 1 of a machine having another form of actuator.

Figure 6 is an enlarged detail sectional view showing a clutch mechanism embodying the part in the construction shown in 50 Figure 5.

Figure 7 is a fragmentary detail view of 55 operating means for such clutch mechanism.

This pressing machine comprises general-

ly coacting pressing elements, one of which 55 is movable toward and from the other, the latter being supported by the frame of the machine, a lever carrying the movable element, the lever being pivoted to the frame, a power member and mechanism for transmitting the motion of the power member to said lever, such mechanism including means by which the power, if applied, when the press is open, is ineffective and works idly on 65 said lever, and is only effective on said lever after the press has been closed by hand.

As here illustrated, the movable pressing element is arranged above the stationary pressing element and is movable upwardly 70 and downwardly toward and from the stationary element.

1 designates the lower pressing element or buck which is mounted upon a bracket 2, which, in turn, is mounted upon a table 3 supported by the frame 4 of the machine, all 75 of which parts may be of any suitable form, size and construction.

6 is the upper pressing element or head which is carried by a lever 7 pivoted between 80 its ends at 8 to the upper end of an upwardly extending standard 9 provided on the frame 1, this lever 7, having a suitable handle 10 by means of which the press head 6 is first brought down toward or onto the work spread on the lower buck 1.

11 designates the power member which, as here shown, is a lever pivoted at 12 to the frame 4 near the bottom thereof. The motion transmitting means between the member or lever 11 and the lever 7, which carries the press head comprises a main toggle link 13 mounted at its lower end on the pivot 12 and usually formed rigid with the lever 11, a folding toggle link 14 including parts 15 and 16 pivoted together at 17 and pivoted respectively at 18 to the rear arm of the lever 7 and at 19 to the upper end of the link 13, the parts 15, 16 being pivoted together at 17 by a stop joint arranged to stop the folding of the link 14 100 when the joint 17 has passed into or slightly beyond the dead center line of the toggle parts 15, 16.

Owing to the stop joint, no latches or locks are necessary and the toggle is self-contained or self-locking. Thus, upon the movement of the press head downwardly 105 from its position shown in Figure 2, the

folding link 14 moves from its folded position shown in Figure 2 to its straight position shown in Figure 1 and such movement is relative to the main toggle link 13, which 5 remains stationary while the folding link 14 is moving from folded to straight position. Thereafter power is applied to the lever 11 either by foot or by power or motor driven mechanism and the toggle links 13, 14 10 straightened and heavy pressure is applied to the lever 7 and the press head 6, and in so doing the links 13, 14 move from the position shown in Figure 1 toward the dead center line of the toggle links 13, 14, that is, 15 a straight line passing through the pivots 12 and 18. If power is applied to the lever 11 before the head 6 has been brought down to such a point that the folding link 14 is straightened, the folding link will fold up 20 instead of transmitting motion to the lever 7 and, hence, the operator, although he may apply pressure or power to actuate the lever 11, cannot apply power to the upper press head while his hands are between the pressing 25 elements.

The stop joint between the parts 15 and 16 of the folding link 14, in addition to the pivot 17, includes an arm 20 carried on one 30 of said parts as part 15, the arm extending across the pivot 17 and overlapping the part 16 in order to engage the part 16 after the folding link 14, consisting of the parts 15, 16, has been straightened. Usually, the arm 20 is provided with an adjustable engaging 35 end, as a set screw 21. As the use of stop joints in toggles is well known and further, as there are many kinds of stop joints, further description of such stop joints is 40 thought to be unnecessary and it will be understood that any stop joint may be employed.

Also, in order to adjust the press head 6 to the thickness of the work being operated upon, one of the parts of the folding link 45 14 is adjustable endwise to lengthen or shorten the link 14 and, as here shown, the part 15 is adjustable endwise, it being provided with a turn-buckle construction including an intermediate part 22 having right 50 and left hand threaded connection with the end sections, the latter being pivoted at 17 and 18 to the part 16 and to the lever 7 respectively.

Also, in order to avoid the use of latches 55 and other additional parts, means is provided for limiting the movement of the pivot or the joint 19 of the main toggle after it has passed into or beyond the dead center line as the main toggle and, as here shown, 60 the link 13 and folding link 14 are connected by a stop joint 23 of any suitable construction, that here shown as being similar to the stop joint between the parts 15 and 16 of the folding toggle link 14.

65 The power lever 11 is preferably actuated

by a motor driven actuator as a cam 24 mounted upon a constantly rotating shaft 25, coacting with a follower carried by the lever 11 and shiftable into and out of connection with the cam. As here shown, this 70 follower is a rock arm 26 pivoted at 27 on the lever 11 and having an engaging end as a roller 28 movable under the cam 24, it being normally in the position shown in Figure 3 in which it is out of position to engage the cam and being movable at will under the cam by suitable operator operated means when the low point of the cam comes opposite to the roller. The cam 24 is of 75 such shape that there is a clearance between 80 the heel or low point of the cam and the follower. This clearance permits the follower to move under the low point of the cam and also to release itself from the cam under the influence of the weight 29 after the lever 11 85 has been depressed by the cam.

As here illustrated, the follower 26 is moved into and normally held in its inactive position by a weighted arm 29 and is shifted into operative position so that its roller 28 90 is under the cam 24 by a suitable mechanism here shown as comprising a lever 30 pivoted at 31 to the bottom of the frame 4 and having an arm engaged with an angularly extending arm 32 on the follower 26, and an 95 actuating lever or treadle 33 pivoted at 34 to the bottom of the main frame having a front plate 35 at its outer end, and engaged at its inner end as by a pin-and-slot connection at 36 with the lever 30. Obviously, upon 100 the depression of the lever 33, the lever 30 will be rocked on its pivot 31 and depress the arm 32, thus rocking the follower against the holding action of the weighted arm and moving the roller 28 under the cam 105 24. As the cam 24 is constantly rotating, it will act upon the roller 28 and thus depress the follower 26 and the lever 11, and the lever 11 will move the toggle link 13 forwardly into the dead center line of the main 110 toggle consisting of the links 13, 14 and, in so doing, apply pressure to the upper press head 6, it being understood that the press head has been pulled downwardly from its 115 position shown in Figure 2 to that in Figure 1, so as to straighten the folding link 14 before the foot lever 33 has been operated to connect the lever 11 or the follower 26 to the cam 24. In Figure 1, the toggle links 120 13, 14, power lever 11, cam 24 and follower 26 are in their positions assumed just after the head 6 has been pulled down toward the buck 1 by hand and the follower has moved under the low point of cam 24, and prior to the time that the high point of the cam 24 125 will engage the follower 26 and depresses the lever 7 to further straighten the toggle links 13, 14 and apply heavy pressure. When in this position the lever 11 is adjacent to stop 42 and when the lever 11 is depressed 130

by the cam it moves downwardly away from stop 42 from the position shown in Figure 1. This movement of the lever 11 is a relatively small one it being sufficient to move

5 the toggle links 13 14 into their dead center line. When the toggle links are in their dead center line, they automatically lock the press closed without the use of locks or latches, this being a function incidental to 10 toggles having stop joints. In the event this lever 33 is operated before the press head 6 has been brought down by hand and before the folding link is straightened, the lever 11 and the toggle link 13 will be actuated but 15 such actuation will be ineffective upon the lever 7, as it will merely tend to fold the folding link 14 to a greater extent than normally.

After the pivots 12, 19 and 18 have been 20 brought into line, the cam 24 continues to revolve without effecting a movement of the press head, and only upon operation of the kick off pedal 33 at an appropriate time will the toggle 13, 14 be broken to open the 25 head.

To open the press, the toggle link 13 is actuated to move the joint 19 rearwardly out of the dead center line, so that the press 30 will open by the usual counterweight 37 acting on the rear arm of the lever 7 and by a spring 38 connected at one end to the lever 11 and at its other end to the frame. The spring 38 acts to move the main link rearwardly and in so doing giving sufficient 35 impulse to the folding link 14 to cause it to unfold or start unfolding so that the counterweight completes the unfolding.

After the starting impulse has been given by the kick off lever 33, the main toggle 14, 40 13 continues to open under the influence of the weight 37 and spring 38 and the joint 19 of the main toggle travels rearwardly in an arc having a slight downward movement and the joint 18 at the upper end of the main 45 toggle travels downwardly and forwardly in an arc faster than the joint 19 travels rearwardly and downwardly for the reason that the rear arm of the yoke lever 7 is of a short radius compared with that of the link 50 13 and also as this rear arm is horizontal when the press is closed and in a horizontal line with the axis 8 its forward movement begins at the very start of the opening movement of the yoke 7 while the link 13 stands 55 when the press is closed out of a vertical line passing through the pivot 12 of the link 13 and the joint 19 is well to the rear of such vertical line. Immediately upon the starting impulse being given to the link 13 by 60 the depression of the kick off lever 33, the pivot 18 moves downwardly and forwardly at a faster rate than the pivot 19 moves rearwardly and downwardly in its arc. This movement in effect locates the pivot 17 rearwardly relatively to a straight line passing

through the pivots 18 and 19 so that the sections 15 and 16 of the toggle link 14 fold about the joint 17.

As here shown, this main lever is operated to open the press by what, for convenience, is called a kick off lever 39 pivoted at 40 to the bottom of the frame having one arm arranged under the front end of the lever 11 and the other arm provided with a 70 pedal plate 41. A suitable stop 42 is provided for limiting the opening movement of the main link 13, this stop being here shown as carried by the frame and coacting with the lever 11 to limit the upward movement thereof by the spring 38.

The shaft 25 on which the cam is mounted is actuated by a suitable motor 43 mounted on the frame and connected to the shaft by suitable gearing located in the casing 44, the casing 44 being also supported in any suitable manner on the main frame 4.

Instead of a constantly moving cam, any other power mechanism may be embodied and, as shown in Figures 5 and 6, an intermittently actuated cam 45 may be used 80 coacting with a lever 46 corresponding to the lever 11, the cam being always engaged with the lever 46. This cam is mounted upon an intermittently movable shaft 47 which is driven by a constantly running electric motor 48 the shaft of which is connected to the shaft 47 through a mechanism including a half revolution clutch located in the casing 49, this clutch being operated to connect the shaft 47 to the motor shaft or a shaft driven by a motor, by a manually operated shifting lever 51.

As here illustrated, the shaft 47 is connected to the motor shaft 52 through a worm 53 mounted on the shaft 52, and meshing with a worm gear 54 mounted concentric with the shaft 47 and rotatable about the same, and a clutch for engaging and disengaging the worm 54 to the shaft 47. This clutch may be of any suitable form, size and construction, that here shown being a disk clutch consisting of a series of disks 55 interlocked with arms 56 projecting from one side of the worm gear 54 and disks 57 interlocked with a hub 58 keyed to the shaft 47, the disks 57 being interleaved with the disks 55, the disks being normally separated so that the clutch is disengaged and being pressed together by a pressure plate operable to compress the disks by the lever 51.

59 designates the pressure plate having a hub 60 slideable axially on the shaft 47 in one direction against the action of the compression spring 61 interposed between the hub 58 and the plate 59, so that the spring tends to press the plate 59 to the right to disengage the clutch disks. The pressure of the plate is transferred to the disks to compress the same through a series of springs, 125 62, encircling studs projecting

from the plate 59, each spring 62 thrusting at one end against the plate and at its other end against the endmost disk 57.

The plate 59 coacts with the means for holding the clutch engaged or the plate 59 shifted, during each half revolution and for permitting it to be shifted to the right to disengage the clutch at the end of each half revolution by the spring 61. This means, as here shown, comprises an annual track or cam 63 arranged concentric with the shaft 47 and having diametrically opposite notches 64, the track coacting with the followers or rollers 65 on the outer or right hand face of the plate 59 and the notches 64 receiving such followers at the end of each half revolution. The track 63, as here shown, is mounted on an end plate 66 of the casing 49. The hub 60 of the pressure plate 59 extends outside of the end plate 66 and has a suitable groove for receiving the fork 67 at the end of the shifting lever 51.

Obviously, upon the shifting of the plate 59 inwardly to the left against the action of the spring 61, the pressure of the plate 59 will be transferred through the springs 62 to the disks 55, 57 and the clutch will be engaged and, hence, the worm gear 54 clutched to the shaft 47; and such movement of the plate 59 to the left will move the rollers 65 out of the notches 64 so that the plate will be rotated and the rollers 65 will travel along the track 63 during a half revolution of the shaft 47 with the worm gear 54 until the rollers 65 again register with the notches 64 and the spring 61 is free to shift the plate 59 to the right carrying the rollers into the notches 64 and disengaging the clutch, so that the shaft 47 and the cam 45 are again stationary.

The lever 51, as here shown, is an angle lever pivoted at 68 and connected to a suitable handle lever 69 by a link 70, the lever 69 being pivoted at 71 to the frame. This lever 69 is located in any desired position to be conveniently operated by the operator.

In operation, the operator pulls down the upper press head, as before, in the construction shown in Figures 1 and 2, straightening the toggle links 13' and 14' and then the operator pulls forwardly on the lever 69 and thus operates the lever 51 to throw in the half revolution clutch, and hence causing the shaft 47 and the cam 45 to make a half revolution and depress the lever 46 and hence straighten the main toggle consisting of the links 13' and 14'.

After the pressure has been applied long enough to suit the operator, the handle 69 is again operated and the clutch makes another half revolution permitting the lever 46 to rise and the main toggle to open and, in so doing, cause the second toggle consisting of the folding links 15' and 16' to fold up. In this construction, the main toggle

consisting of the links 13' and 14' does not quite move into the dead center line.

As the cam 45 moves away from the lever 46, the spring connected to such lever 46 causes the lever to follow the cam, the counterweight also facilitating such operation. As the joint of the main toggle moves rearwardly, the joint connecting the upper link of the main toggle and the yoke lever moves downwardly and forwardly faster than the main joint of the toggle moves rearwardly and downwardly, thus causing the small toggle comprising the main toggle link 14' to fold as before pointed out in connection with the toggle mechanism shown in Figure 1.

In the construction shown in Figures 5 and 6, if the operator operates the lever 69 to throw in the clutch before he has brought down the press head into pressing position, the movement of the toggle link 13' will be ineffective upon the lever 7, which carries the press head for the reason that the folding link 14' is in its folded position.

It will be noted that in both forms of this invention, the power lever remains stationary while the press head is being brought down by hand and that no locks or latches or other similar devices to be operated are used and, further, that the machine is rendered absolutely safe without the use of safety first appliances, guards, cages and the like, such as are used on various types, punch presses and garment presses and the like.

Neither the follower and cam mechanism nor the clutch per se forms any part of my invention, and I make no claim thereto, as such follower and cam mechanism and the clutch are the inventions of others. Such cam follower and mechanism and clutch in so far as this invention is concerned is the mechanism or the adaptation of the mechanism of one form of a commercial pressing machine to which my toggle mechanism is applied.

What I claim is:

1. A pressing machine comprising a frame, coacting pressing elements, one of which is movable toward and from the other, a lever pivoted to the frame and supporting the movable pressing element and actuating means comprising toggle links pivoted together respectively to said lever and to the frame, the link connected to said lever consisting of two parts pivoted together, forming a toggle, the parts of the last mentioned toggle being pivoted together by a stop joint.

2. In a pressing machine, the combination of a frame, coacting pressing elements, one of which is movable toward and from the other, a lever pivoted to the frame and supporting the movable element and actuating means comprising a main toggle and a second toggle forming one of the links of the main toggle, the joint of the second toggle

- being a stop joint, all whereby the movable pressing element and its supporting lever is movable toward pressing position to straighten and lock the second toggle with-
 5 out moving the main link of the main toggle, and actuating means acting on the main link of the main toggle to move it about its pivot.
3. In a pressing machine, the combination
 10 of a frame, coacting pressing elements, one of which is movable toward and from the other, the latter being mounted on a frame, a lever carrying movable pressing element and actuating means for the lever comprising
 15 a power member and mechanism actuated by the power member and being ineffective on said lever when actuated, when the movable element is in its open position and said mechanism including self-contained
 20 means movable in position to transmit motion and to lock in such position by the movement of the lever to carry the movable element into pressing position.
4. In a pressing machine, the combination
 25 of a frame, coacting pressing elements, one of which is movable toward and from the other, a lever carrying the movable pressing element and pivoted between its ends to the frame and actuating means for the lever
 30 comprising a power member and mechanism actuated by the power member comprising a main toggle consisting of an upwardly extending main link pivoted at its lower end to the frame, a folding link including parts
 35 pivoted together by a stop joint and pivoted respectively to the rear arm of said lever and to the main link whereby the folding link is straightened and locked by stop joint when the movable element is preliminarily moved toward pressing position, the rear arm of the lever and the links, pivots and joints of the toggle being arranged and related so that the pivot connecting the folding link of the toggle and the rear arm of said lever travels forwardly faster than the main joint of the toggle passes rearwardly upon the initial opening movement
 40 of the main toggle link.
- the main toggle link being arranged in inclined position out of a vertical line passing through the pivot of the main link when the toggle is in straightened position, whereby upon the opening movement of the main toggle link the joint connecting the parts of the folding link of the toggle and the rear arm of said lever moves downwardly and forwardly faster than the main joint of the toggle passes rearwardly.
5. In a pressing machine, the combination
 45 of a frame, coacting pressing elements, one of which is movable toward and from the other, a lever carrying the movable pressing element and pivoted between its ends to the frame and actuating means for the lever comprising a power member and mechanism actuated by the power member comprising a main toggle consisting of an upwardly extending main link pivoted at its lower end to the frame, a folding link including parts
 50 pivoted together by a stop joint and pivoted respectively to the rear arm of said lever and to the main link whereby the folding link is straightened and locked by the stop joint when the movable element is preliminarily moved toward pressing position, the rear arm of the lever and the links, pivots and joints of the toggle being arranged and related so that the pivot connecting the folding link of the toggle and the rear arm of said lever travels forwardly faster than the main joint of the toggle passes rearwardly upon the initial opening movement
 55 of the main toggle link.
6. In a pressing machine, the combination
 60 of a frame, coacting pressing elements, one of which is movable toward and from the other, a lever carrying the movable pressing element and pivoted between its ends to the frame and actuating means for the lever comprising a power member and mechanism actuated by the power member comprising a main toggle consisting of an upwardly extending main link pivoted at its lower end to the frame, a folding link including parts
 65 pivoted together by a stop joint and pivoted respectively to the rear arm of said lever and to the main link whereby the folding link is straightened and locked by the stop joint when the movable element is preliminarily moved toward pressing position, the rear arm of the lever and the links, pivots and joints of the toggle being arranged and related so that the pivot connecting the folding link of the toggle and the rear arm of said lever travels forwardly faster than the main joint of the toggle passes rearwardly upon the initial opening movement
 70 of the main toggle link.
7. In a pressing machine, the combination
 75 of a frame, coacting pressing elements, one of which is movable toward and from the other, a lever carrying the movable pressing element and pivoted between its ends to the frame and actuating means for the lever comprising a power member and mechanism actuated by the power member comprising a main toggle consisting of an upwardly extending main link pivoted at its lower end to the frame, a folding link including parts
 80 pivoted together by a stop joint and pivoted respectively to the rear arm of said lever and to the main link whereby the folding link is straightened and locked by the stop joint when the movable element is preliminarily moved toward pressing position, the rear arm of the lever and the links, pivots and joints of the toggle being arranged and related so that the pivot connecting the folding link of the toggle and the rear arm of said lever travels forwardly faster than the main joint of the toggle passes rearwardly upon the initial opening movement
 85 of the main toggle link.

In testimony whereof, I have hereunto signed my name at Syracuse, in the county of Onondaga and State of New York, this 24th day of October, 1923.

ALEXANDER J. SOCIA.
